DESIGN FOR A MICROPHONE STAND

Richard M. Somers, West Orange, N. J., assignor
to Thomas A. Edison, Incorporated, West
Orange, N. J., a corporation of New Jersey

Application November 23, 1944, Serial No. 116,509

Term of patent 14 years

(Cl. D26—14)

To all whom it may concern:

Be it known that I, Richard M. Somers, a citizen of the United States, residing at West Orange, in the county of Essex and State of New Jersey, have invented a new, original, and ornamental Design for Microphone Stand, of which the following is a specification, reference being had to the accompanying drawing, forming part thereof.

Figure 1 is a front elevational view of a microphone stand showing my new design.

Figure 2 is a rear elevational view of the stand shown in Figure 1.

Figure 3 is a side elevational view of the stand shown in Figure 1.

Figure 4 is a top plan view of the stand shown in Figure 1.

I claim:

The ornamental design for a microphone stand, as shown.

RICHARD M. SOMERS.
